UNITED STATES PATENT OFFICE

ALBERT W. SMITH AND RICHARD B. JONES, OF YOUNGSTOWN, OHIO

FURNACE

Application filed August 12, 1921. Serial No. 491,716.

Our invention relates to heating furnaces, and particularly to open hearth furnaces.

An object of our invention is such a furnace wherein the fuel is mixed and directed 5 into the combustion chamber by differences in velocity and pressure of constituents of the fuel.

A further object of our invention is such a device which is simple in construction and 10 easy to operate.

A further object of our invention is the provision of means whereby the products of combustion may be readily removed from the furnace during the operation of the 15 same.

Further objects will be apparent upon reading the following description taken in connection with the accompanying drawings, in which

20 Figure 1 is a sectional elevation of a furnace embodying our invention;

Figure 2 is a section on the line II—II of Figure 4;

Figure 3 is a section on the line III—III 25 of Figure 2, and

Figure 4 is a section on the line IV—IV of Figure 3.

The furnace shown in the drawings comprises the usual hearth 1, gas uptakes 2 and 30 3 and air uptakes 4 and 5. The gas and air pass through the usual regenerators 6 and 7 in a well known manner. The furnace is provided with a roof 8 of any desired construction and material.

35 A blower 9 operated by any suitable means is connected to a conduit 10 provided with a valve member 11 operated by any suitable means 12. The valve member 11 is pivoted at 13. When the valve member is in the

40 position shown, the air is conducted through the conduit 10 into and through a recuperator 14 or other suitable heating means. From the recuperator the air is conducted through the conduit 15 and is directed into 45 the chamber 16, shown in Figure 2. The air issues from the chamber 16 in three jets, 17, 18, and 19. The jets 17 and 18 act to force the main volume of air which comes up through the uptake 4 over into the mixing

50 chamber where it will be intimately mixed with the gas coming up through the gas uptake 2.

The air issuing from the jets 17 and 18 is under considerably higher pressure than the air in the uptakes and by reason of the 55 difference in pressure and velocity of the air issuing from these jets, the main portion of air is forced into contact with the gas and is intimately mixed therewith. The air issuing from the jet 19 forces the mixture of 60 air and gas from the mixing and partial combustion chamber into the furnace where combustion is completed. By reason of the difference in pressure and velocity of the directing jets, the air and gas are given a 65 rapid and intimate mixture resulting in a rapid and efficient combustion.

Discharge ports 20 are provided near the air uptakes, as shown in Figure 2. During the period of combustion there will be no 70 substantial movement of either combustion gases or spent gases in the discharge ports at that end of the furnace because the air jets 17 and 18 will have sufficient velocity to force the main quantity of air for combustion into the air port, and will not aspirate the burned gases from the furnace chamber back into the air port. Furthermore, the force of the jets 17 and 18 will be sufficient to deflect the main body of air 75 rising from the uptakes and will allow no substantial part of it to travel through the discharge ports into the combustion chamber.

The air used in the directing and mixing 80 jets is supplied by a blower 9 or other suitable means, and may be directed to either end of the furnace by the conduits 10 and 15 or the conduits 21 and 22, which are exact 85 duplicates of the conduits 10 and 15. In both instances the air is conducted through a recuperator 14 or other heating device. It will be apparent, therefore, that the directing and mixing air is heated by the waste 90 gases from the furnace to a temperature approaching that of the main volume of air 95 and gas.

During the period that combustion is taking place at one end of the furnace, the 100 products of combustion pass from the other

end of the furnace. During this period the air jets at the exit end of the furnace will not be supplied with air and the products of combustion will pass out of the furnace entirely under the control of the stack draft.

5 There are three paths of egress for the exhaust gases. First, they discharge through the gas port and down to the gas regenerative chambers through the uptakes 2 and 3, as shown in Figure 2; second, through the air port into the air uptakes 4 and 5 down to and through the regenerative chambers; third, through the discharge ports 20 and by the same path from the regenerators to the stack. No substantial amount of gases will pass through the air jet passages as shown in the drawings, as these are relatively small. However, such passages may be increased in area so as to permit the gases to pass out therethrough.

20 From the foregoing it will be noted that there are no valves or dampers for directing the passage of the fuel into, or the spent gases from the furnace through the ports.

25 The operation is controlled entirely by the difference in velocity of a constituent of the fuel, and all elaborate mechanisms of water cooled dampers and valves are eliminated.

Throughout the specification and claims 30 we have used the terms "gas" and "gaseous medium". These terms when used herein have their physical meaning and are to be interpreted in a broad sense. For instance, the word "gas" is not to be interpreted herein as meaning merely fuel gas, but includes fuel gas, air, or any other gaseous fluid.

Our invention has many advantages, in that a simple and efficient arrangement is 40 provided for mixing and directing the fuel and the spent gases; further advantages reside in the provision of means whereby valves and dampers and other complicated and expensive devices are eliminated. Many 45 other advantages will be apparent to those skilled in the art.

While we have shown and described one embodiment of our invention, we desire it to be understood that we are not limited to the exact arrangement shown and described, as many changes may be made in the details without departing from the spirit of our invention.

We claim:

50 1. The method which consists in conducting gas into the port of a furnace and conducting air into the region of the port and subjecting the air therein to a transverse gaseous current to direct said air into the 55 port and mix it and the gas together and to a longitudinal current for conducting the mixture into a combustion and heating chamber.

2. In a heating furnace, the combination 60 of entering gas and air ports, auxiliary gas

discharge ports, means for supplying a jet of gaseous medium at a velocity to direct the combustible gases into the furnace through the entering ports and prevent said gases from entering the furnace through the 70 discharge ports at the intake end of the furnace.

3. In a heating furnace, the combination 75 of a regenerative chamber and a recuperative chamber through each of which a part of the fuel air is passed at different pressure and velocity.

4. In a heating furnace, the combination 80 of two heating chambers for the air whereby the air is supplied in two parts, and means for giving said parts different pressures and velocities.

5. In a heating furnace, the combination 85 of air and gas entrance passages and means for mixing and then directing said air and gas by separate streams of a gaseous medium of differing velocity.

6. In a furnace, a gas inlet port, an air inlet port adjacent thereto, auxiliary air ports on each side of the air inlet port for 90 effecting a mixture of the gas and air, and an auxiliary air port for directing the mixed air and gas into the furnace.

7. In a furnace, the combination with air and gas inlet ports, discharge ports connecting with said air inlet port and a supply duct therefor, of auxiliary air ports and means for supplying air thereto at such velocity as to cause all the air from said duct to pass through said first-mentioned air port.

8. In a furnace, an air supply port, a duct leading thereto and a discharge port connecting with said supply port and duct, an auxiliary port and means for supplying a gas therethrough to prevent the passage of air from said duct through said discharge port.

In testimony whereof we have hereunto set our hand.

ALBERT W. SMITH.
RICHARD B. JONES.
